WINDOW SCREEN

Albert P. Zeller, Baltimore, Md.

Application February 6, 1934, Serial No. 709,906

3 Claims. (Cl. 156—14)

This invention refers to windows and more particularly to wire screening for same, and has for its object to provide a screen using metal framing that will work effectively; will permit the screen or netting to be tightened while the frame is in place, will permit the insertion and removal of the screen proper with facility and which will have means for connecting the moldings used on the frame that will effectively connect into each other and keep the frame substantially braced. Another object is to provide an arrangement for adjusting the position of the screen in a window frame, and to provide a lock that will prevent the window screen from being opened in an unauthorized way.

Various inventions have been developed using metals for the framework of window screens, but such in general use a flat sheet of metal formed to suit their particular designs, and are not in general suitable for use with windows using metal frames of modern types. This invention provides for a window screen that may be adapted for use with the conventional forms of metal windows. It is made from metal die-formed into structural shapes or rails that are cut to make a suitable frame, and to coact with side members that guide and hold same, and a metal molding is provided for holding the screen or netting and give a finished appearance to the whole screen.

In the drawings which illustrate by way of example, an embodiment of this invention:

Figure 1 is a front view of a movable screen for windows embodying this invention, and with parts broken away to indicate the general construction of the corners and center mullions.

Figure 2 is a front view of a stationary screen for windows of a special type.

Figure 3 is a horizontal section through the frame construction along line 16—16 of Figure 1.

Figure 4 is a vertical section through the frame construction along line 17—17 and showing the rubber bumper in bottom of frame, of Figure 1.

Figure 5 is a horizontal section through frame construction along line 18—18 of Figure 2.

Figure 6 is a detail of the rack used in connection with the side rail for holding the window screen in adjusted and locked positions.

Figure 7 is a plan view of rack, shown mounted on side rail,

Figure 8 is an end view of the rack, shown mounted on side rail,

Figure 9 is a section of side rail, used in connection with the screen.

Similar reference characters refer to similar parts throughout the drawings.

In the construction shown, 1 represents a conventional window frame to which is attached a side rail 2 of aluminum or other metal, die-formed in the shape indicated. This shape has a flat base 3 and a projecting shoulder 13 that has a quasi-wedged like section, the portion near the base being the restricted portion. One side rail may have an additional arrangement of rack teeth 4 to provide an arrangement for adjusting the window height of screen in open positions. The screen frame itself is provided with a die-formed section rolled to the shape indicated. Its main body portion 5 is flat and one side 6 is channelled to fit and slide over the shoulder 13 of the side member of rail. The other side of 5 is provided with a lip 8 which is suitably slanted, as well as the rear of the channel portion to provide a tightening effect on the screen netting when inserted in the frame.

The molding 31 is of flat material with its small edges slanted to conform with the slanted portions of the main body portion of the frame, as indicated at 9 on both the parts. The molding may be provided with ribs 10 or other suitable embossed or raised lines on its upper surface to give it an attractive design. Suitable holes for screws are provided at 11 in the molding. These holes align with holes screw-threaded in the main body portion 5 at 12. The side rails are provided with holes 23 for holding screws.

At the corners of the frame, the frame members are cut to a key-form 14 to permit the same to be locked together and tightened against movement or shrinking action. This same type of lock is used for mullions 22 and other joints required in the frames and moldings for conventional or special windows.

The rack 15 provided on the side rail 3 is provided with the teeth 4 which are preferably constructed as indicated in the drawings, to permit the catch on the lock to slide over same and then rest on their ledges 34 with a slot 24 at the bottom for receiving the catch when desired to lock same. The lock is preferably of the type indicated and is attached to the screen frame in a suitable manner. A rubber bumper 30 is provided in the bottom rail.

The side rails are provided only at the sides of the frame. In the special form of frame 25 shown in Figure 2 the metal of the frame is bent to suit the type of window, and the joints 14 are locked in with the type of headed lock joint referred to before. It is secured to the window frame.

When the screens are mounted on the windows,

the frame engages with the side rails and may be raised, and held on the rack in various positions of opening, or may be locked down when shut by allowing the catch of the lock to engage in the slot 24 the lock 19 being provided on the inside or house side of the window. When it is desired to replace the screen itself or netting 20, it is done so by removing the molding, which is readily done by unscrewing the screws from same and the frame. The molding is taken out, being detached by lifting. The netting is then removed. On replacing the netting, the netting is inserted in the frame so that the side and top portions are inserted in the inside of the main body sections. The molding is then inserted in the frame on top of the netting, and tightened down. While this is being done the slanting sides 9 of the molding and the main body portions, coact and pull the netting taut. The mullions are provided in the screen frames where needed, and have the so-called headed-lock joint for securing them substantially in place, which also greatly strengthens the construction at the same time without detracting from its appearance. While but one general type of construction is shown in the drawings, it is not desired to limit this application for patent to that particular form or in any other way, otherwise than limited by the prior art, as it is well known that other constructions could be used that would employ the same principles and come within the scope of the appended claims.

What is claimed is:

- 35 1. A stationary window screen frame comprising sections having projecting wedgelike portions, each with an enlarged head theron, and recesses structurally corresponding to receive and separably hold said first-mentioned portions and co-act therewith to make the frame knock-down in adaptability.
2. A stationary window screen comprising a sectional frame each section being provided on its respective ends with an interlocking portion for cooperative connection to an adjacent section, one of each of said cooperating interlocking portions having a projecting member with converging sides surmounted by an enlarged head, and the portion cooperating therewith having a recess to closely receive and retain same, a recess on the face of the frame having sides provided with a plurality of bevels, a screen to fit therein and against said bevels, a molding with surfaces adapted to fit closely against said bevels and tighten up on said screen, and means for securing said molding to the frame.
3. A window screen of the class described, comprising in combination a metal frame having sections of channel form, the interior surface of the channel sections being inwardly bevelled toward the middle with a plurality of bevels and their exterior surface being formed to provide a finished form of conventional design, a recess extending along the side of the frame having an interiorly enlarged aperture for a runway along the same, a plurality of interlocking joints having a closely fitting connection that cannot be unlocked by pulling or pushing along the plane of the frame, a screening for the same, a molding to fit into the bevels of the frame and clamp and tighten the screening therein and lock over said interlocking joints, and means for tightening the molding to the frame, said recess adapted to cooperate with rail means to hold the frame against sidewise movement and permit vertical opening and closing of the screen.

ALBERT P. ZELLER
